JOSEPH T. ZOTTOLI, OF BOSTON, MASSACHUSETTS.

GEAR-PUMP.

1,284,028.

Specification of Letters Patent.

Patented Nov. 5, 1918.

Application filed August 8, 1917. Serial No. 185,160.

To all whom it may concern:

Be it known that I, JOSEPH T. ZOTTOLI, a citizen of the United States, residing at Boston, in the county of Suffolk and Commonwealth of Massachusetts, have invented a certain new and useful Improvement in Gear-Pumps, of which the following is a specification, reference being had therein to the accompanying drawings.

10 The invention relates to a new and useful improvement in gear pumps. It is especially intended for application to use in a device for automatically pumping out water from a leaky boat or for pumping water from the 15 water compartments of a submarine when it is desired to remove the water from the water compartments to permit the boat to rise to the surface.

One object of the invention is to provide a 20 pump of the above mentioned character which is connected with a hose or pipe leading from the boat or compartment which is to be pumped out, the hose being long enough so that while one end of it opens into the 25 compartment which is to be pumped out, the pump is connected with the other end of the hose and may be passed overboard, and the force of the water while the boat is in motion and the pump is being dragged in the 30 water, will actuate the pump automatically.

The invention will be fully understood from the following description, taken in connection with the accompanying drawings, and the novel features thereof will be pointed 35 out and clearly defined in the claims at the close of this specification.

In the drawings, Figure 1 is a vertical section of a device embodying the invention.

Fig. 2 is a view of a portion of the parts 40 shown in Fig. 1, the upper portion of the box or casing being partly broken away and showing the gears in the position they will be after they have revolved part way around from the position shown in Fig. 1.

Fig. 3 is a vertical section on line 3—3 of Fig. 1.

Fig. 4 is a side view of a boat in the water and equipped with the apparatus, showing the gear pump submerged in the water out 50 side of the boat, and the hose leading therefrom over the side of the boat and extending down into the water which is being pumped out of the bottom of the boat.

Fig. 5 is a plan view of a submarine, showing 55 a modified form of casing for the gears, which is especially adapted for a submarine.

Fig. 6 is a detail view showing on a larger scale the pump shown in Fig. 5.

Referring now to the drawings, A and B respectively denote two gears which are exactly alike and which mesh with each other, each being journaled in bearings in the two end walls 1, 2, of the gear case or box. In the form shown in the drawings, each gear is formed with a cylindrical projection 3 at 60 each end which serves as a journal and rotates in a bearing in the end wall of the case. Any suitable form of journal, however, may be employed. It is desirable that the journal shall fit as closely as possible in the bearing to allow easy rotation, yet be packed in such manner as to prevent, as far as possible, leakage of water through the bearings.

The end walls 1, 2 of the casing preferably have a flaring top and a more contracted lower end as shown in Figs. 1 and 2, the said casing being open at the bottom and at the top.

Each of said gears is formed with teeth 4, preferably four in number, the periphery of 80 each tooth being convex in cross section and between the teeth are depressions or pockets 5 which are concave in cross section, that is, both sections being taken transversely of the axis of the gear. The radius of curvature of 85 the periphery of the teeth should preferably be the same as the radius of the pocket, but the pocket should be of a greater length of arc than the arc of the tooth. The preferable proportion is to make the arc of the 90 curve of the pocket twice that of the tooth. If four teeth are employed as shown in the drawings, the tooth should have an arc of about 90°, and the pocket should have an arc of about 180°.

The two gears should be so mounted in relation to each other that the teeth of each will successively and alternately bottom in the pockets of the other.

A hood 7 is provided for the gears, said 100 hood extending the full length of the casing, that is, the full distance between the two end walls 1, 2 and having two wing portions 8, 9, which respectively extend down over the upper sides of the two gears, that is, over the 105 sides which are toward the entrance to the casing, and which is on the upper side when the device stands in the position shown in Figs. 1 and 2. Said hood is formed with a stem portion 10 and with an aperture 11 extending from the inner end of the hood through the stem 10. The outer end of the 110

stem is adapted to be connected with a hose 12 whose other end will open into the interior of the boat 13 or compartment which is to be pumped out.

5 The lower end of each wing 8, 9, is concaved on a curve whose radius is the distance from the high point of each tooth of the gear to the center of the gear.

Said hood is so adjusted with relation to 10 the gears that as the gears rotate, the high point of each tooth will have a grazing contact with the concave face of the wing 8 or 9 as the case may be, from the time that the high point of the tooth reaches the inner 15 edge of the wing, until it passes off the outer edge of the wing. Also, the length of the arc from the inner edge to the outer edge of each wing, for instance, from the point 14 to the point 15, will be greater than the distance 20 from the high point 16 of one tooth to the high point 16 of the next tooth, so that the high point 16 of one tooth will not ride off of the outer edge 15 of the wing before the high point 16 of the next following tooth 25 begins to engage the inner edge 14 of the wing, in order that there shall be, at no time, an open communication from the passage 11 through the hood to the passages 18 and 21 which lie between the gears and the side 30 walls 19 and 22 of the casing. Thus the water which passes down through the passage 11 can escape only as it is carried out through the pockets of the gears. When the device is thrown overboard, and trolled at 35 the end of the hose 12 with the boat, the casing and its attached parts will be dragged head first, that is, the bell shaped open end will be toward the front, so that the water, during the travel of the boat, will pass into 40 the casing from the larger front end 20 and out through the contracted rear end 17. It is to be noted that viewed in cross section as shown in Fig. 3, the gears are of sufficient length to extend the full length of the space 45 between the two end walls 1 and 2, but viewed at right angles to Fig. 3, as in Figs. 1 and 2, there are spaces 18 and 21 between the walls 19, 22 of the casing, and the lower edges 15, 23 of the wings 8, 9, thus 50 allowing the water to freely pass through these spaces 18, 21 from the larger end of the casing to the smaller end of the casing. As the water rushes through these spaces, or perhaps more correctly, as the casing is 55 dragged through the water, the water will enter the open pockets on the lower side of the wings and the pressure will be against the side of each pocket which is most directly opposed and thus cause the gears to rotate 60 in opposite directions to each other as indicated by the arrows. The teeth as they face the hood will rotate toward each other, and the teeth toward the exit end will rotate away from each other.

65 As the gears thus rotate, each tooth as it

moves past the open lower end of the passage 11 in the hood, will cause a suction down through the passage 11, carrying a pocket full of air, as for instance indicated by the space in the inclosed pocket 5 of gear 70 A shown in Figs. 1 and 2, which will be expelled as soon as the gear has rotated far enough so as to open said pocket down below the lower edge 15 of the wing 8. A similar action takes place by the rotation of the gear 75 B, a pocket full being emptied alternately by the two gear wheels, and each tooth in succession discharges a pocket full. If there is any water in the boat, and if the end of the hose 12 opens into it while the gear pump 80 is trolled in the water outside, as shown in Fig. 4, the suction will draw the water out of the boat and down through the hood and of the gears, whence it will be discharged.

On the upward movement of each tooth 85 there will be a drawing in of a small quantity of water from the outside body of water in which the pump is submerged, but the largest quantity of water drawn in each time will be the amount which can be contained in the small inclosed space 25 formed between two teeth of the two gears on their upward stroke. This inclosed space is very much smaller than the full size of the pocket, and as the amount of water carried out by 90 each pocket is an entire pocket full, the water will be carried out much faster than it can be taken in, thus the water will be gradually drawn out of the boat or compartment which is being pumped out.

100 In the equipment which I especially intend for a submarine, the pump, instead of being connected with a long hose, and thrown overboard as already described, is permanently attached to the interior of the 105 submarine as shown by the casing 30 in Figs. 5 and 6 and is formed with two pipe branches 31, 32, which pass out through the side of the boat, the branch 31 communicating with the entrance end of the casing 110 110 which is headed in the direction that the boat goes, and the branch 32 communicating with the rear end of the casing. These two branch pipes have open outer ends 33, 34, respectively, and as the vessel travels 115 through the water in the direction indicated by the arrow, the water will enter the casing through branch 31 and will enter the pockets outside of the hood 35 and rotate the gears, thereby causing suction through the pipe 36 120 from the interior of the water compartment 37 in the manner already described with reference to the first form of apparatus.

What I claim is:

1. In a gear pump, two intermeshing 125 gears constituting pumping elements, a casing in which said gears are journaled, a hood which extends lengthwise of the gears in position to permit water to pass outside of it through the casing and is formed with two 130

- concave portions which respectively coöperate with said two gears, and which are so located and are concaved on such a radius with relation to the diameter of the gears 5 that during the rotation of the gears, each tooth will form a grazing contact with one of the concave surfaces of said hood during its travel, the length of the arc of the concave surface of the hood being greater than 10 the distance between two adjacent teeth, whereby, as the gear rotates, one tooth will not pass off of the concave portion of the hood until the next following tooth comes into contact with said concave surface of the 15 hood.
2. In a gear pump, two intermeshing gears constituting pumping elements, a casting in which said gears are journaled, a hood which extends lengthwise of the gears 20 in position to permit water to pass outside of it through the casing and is formed with two concave portions which respectively coöperate with said two gears and which are so located and are concaved on such a radius 25 with relation to the diameter of the gears that during the rotation of the gears, each tooth will form a grazing contact with one of the concave surfaces of said hood during its travel, the length of the arc of the concave surface of the hood being greater than 30 the distance between two adjacent teeth, whereby, as the gear rotates, one tooth will not pass off of the concave portion of the hood until the next following tooth comes 35 into contact with said concave surface of the hood, said hood being formed with a stem having an aperture extending lengthwise therethrough from the concave end of the hood.
4. In a gear pump, two intermeshing gears constituting pumping elements, a casting in which said gears are journaled, a hood which extends lengthwise of the gears 40 in position to permit water to pass outside of it through the casing and is formed with two concave portions which respectively coöperate with said two gears and which are so located and are concaved on such a radius with relation to the diameter of the gears 45 that during the rotation of the gears, each tooth will form a grazing contact with one of the concave surfaces of said hood during its travel, the length of the arc of the concave surface of the hood being greater than 50 the distance between two adjacent teeth, whereby, as the gear rotates, one tooth will not pass off of the concave portion of the hood until the next following tooth comes 55 into contact with said concave surface of the hood, said hood being formed with a stem having an aperture extending lengthwise therethrough from the concave end of the hood.
5. In a gear pump, two coöoperating gears 60 each formed with teeth which are convexly curved on their outer periphery transversely of the axis of the gear, concavely curved pockets between the teeth, said pockets being concaved transversely of the axis of the 65 gear, the curves of the teeth having the same radius as the curves of the pockets, the gears being mounted in such manner that the teeth of one are adapted to intermesh with the teeth of the other, and to be bottomed in 70 the pockets of the opposing gear, a casing or box in which said gears are journaled, said box or casing having an open end, the casing having portions which close the ends 75 of the pockets, a hood which extends lengthwise of the gears, said hood being formed with two concaved or recessed portions which respectively coöperate with said two 80 gears and which are so located and concaved on such a radius with relation to the 85 diameter of the gears, that, during the rotation of the gears, the high point of each tooth will form a grazing contact with one of the concave surfaces of said hood during 90 its travel, the length of the travel of each 95 tooth being somewhat greater than the distance between the highest points of two adjacent teeth, said hood being so adjusted with relation to said gears that in the rotation of the gears, the high point of each tooth will have a grazing contact with the 100 concave face of one of said wings, said hood being formed with an aperture extending from the inner end thereof to the outer end thereof.
6. In a gear pump, two coöoperating gears 105 each formed with teeth which are convexly curved on their outer periphery transversely of the axis of the gear, concavely curved pockets between the teeth, said pockets being concaved transversely of the axis of the 110 gear, the curves of the teeth having the same radius as the curves of the pockets, the gears being mounted in such manner that the teeth of one are adapted to intermesh with the teeth of the other, and to be bottomed in 115 the pockets of the opposing gear, a casing or box in which said gears are journaled, said box or casing having an open end, the casing having portions which close the ends 120 of the pockets, a hood which extends lengthwise of the gears, said hood being formed with two concaved or recessed portions which respectively coöperate with said two gears and which are so located and concaved on such a radius with relation to the 125 diameter of the gears, that, during the rotation of the gears, the high point of each tooth will form a grazing contact with one of the concave surfaces of said hood during 130 its travel, the length of the travel of each 130 tooth being somewhat greater than the distance between the highest points of two adjacent teeth, said hood being so adjusted with relation to said gears that in the rotation of the gears, the high point of each tooth will have a grazing contact with the concave face of one of said wings, said hood being formed with an aperture extending from the inner end thereof to the outer end thereof.

tooth over the coöperating concave surface of the hood, being greater than the distance between the high points of two adjacent teeth, whereby, as the gear rotates, the high point of one tooth will not pass off of the concave portion of the hood until the next following tooth comes into contact with said concave surface of the hood, the said hood being formed with a hollow stem having an aperture which extends entirely

through the same from the outer end to the inner end of the hood and opens into the interior of the hood, forming a space which opens into each pocket of the gears successively during their rotation, and a tubular ¹⁵ connection with said stem which is adapted to be connected with the interior of a boat.

In testimony whereof I affix my signature.

JOSEPH T. ZOTTOLI.
